SCALP PROTECTOR

Victoria Parmentel, New Orleans, La.

Application December 6, 1938, Serial No. 244,281

4 Claims. (Cl. 132—36.1)

The invention relates to a hair waving shield and more especially to a scalp protector.

The primary object of the invention is the provision of a device of this character, wherein the same is utilized in connection with a permanent waving machine and serves as a protector to the scalp during the waving operation to avoid burning or otherwise injuring the skin and particularly the scalp of the head as well as avoiding the possibility of the pulling of the scalp during the waving of the hair.

Another object of the invention is the provision of a protector of this character, wherein the same in its entirety is novel and assures perfect protection against scalp pulling or burning, being readily and easily associated with a curler constituting a part of a Croquignole protector and curler during the waving operation of the hair.

A further object of the invention is the provision of a protector of this character, which is simple in its construction, readily and easily handled, thoroughly reliable and efficient in operation, strong, durable, and inexpensive to manufacture.

With these and other objects in view, the invention consists in the features of construction, combination and arrangement of parts as will be hereinafter more fully described, illustrated in the accompanying drawing, which discloses the preferred embodiment of the invention and pointed out in the claims hereunto appended.

In the accompanying drawing:

Figure 1 is an exploded perspective view of the device constituting the present invention.

Figure 2 is a top plan view of the clamp of the device.

Figure 3 is a bottom plan view thereof.

Figure 4 is a vertical transverse sectional view through the clamp.

Figure 5 is an enlarged detail sectional view through the insulator clip of the device.

Similar reference characters indicate corresponding parts throughout the several views in the drawing.

Referring to the drawing in detail, A designates generally the insulator clip, B the clamp, C the curl protector and D the curler element, respectively, of the device, these being associated with each other for use with hair waving machines in effecting the Croquignole curl and are hereinafter described in detail.

The insulator clip A of the device comprises a flat elongated body 10 made from fibrous material, preferably wood, and is relatively thin and flat having an entrance slot 11 therein at the

longitudinal center. This slot 11 extends only for a major extent of the said body and opens through one end while at opposite sides of the slot are the rounded tip portions 12 so that the strands of hair of a group can be passed into the slot in the use of the device, which is adapted for cooperation in conjunction with a clamp for gripping the strands of hair.

The clamp B comprises a pair of clamping bars 13 and 14, respectively, the bar 14 being pivoted 10 at 15 while the bar 13 is a permanent part of a saddle head 16, being formed with a flange 17 at right angles thereto to which the bar 13 is integrally joined and the bar 14 swingably connected thereto by the pivot 15, respectively. Thus 15 the bar 14 is swingable to and from the bar 13. These bars 13 and 14 have a resilient wrapper 18 thereabout, being sheet rubber and made fast thereto in any suitable manner.

For clamping together the free ends of the bars 20 13 and 14, it is desirable that the bar 14 has pivoted thereto at 19 a link 20 and this link has pivoted thereto at 21 a cam locking lever 22 engageable with a keeper terminal 23 provided on the bar 13. When the bars 13 and 14 are locked 25 together upon a strand of hair, they are adapted for association with the curler D. The link 20 is formed with a prong 24 while the saddle head has a notch 25 for accommodating the curler, which is in the form of a turnable pin 26 having 30 a hand operated twister key 27 at one end while at the other end is a cross slotted lug 28. The prong 24 is engageable in the slots in the said lug 28 when the pin 26 fits the head 16 and the prong 35 accommodated within a selected slot in the lug 28 of the curler so that such pin will be held fixed with the clamp in the use of the same.

Adapted to be interposed between the clamp B and the curler D is a felt protector C in the form of a pad 29 having an elongated longitudinally directed slot 30 intermediate of transverse slots 31 and 32, respectively, provided therein, while stitched or otherwise fastened to the top side of this pad 29 is a flap 33, being adjacent to the slot 30 and between the slots 31 and 32, 45 and is adapted for intercurling with the strands of hair when clamped between the bars 13 and 14 and curled about the curler D. On the curling of the strands of hair, the curler D is free of the seat 25 and the prong 24 hereinbefore described. 50

In the assembly of the device, the insulator body 10 is disposed next to the scalp with grouped strands of hair entered in the slot 11 and these grouped strands of hair are clamped between the bars 13 and 14 of the clamp B. Then, the 55

pad 29, which is the protector C, is superimposed on the clamp B with the grouped strands of hair passing through the slot 30, these strands being intercurled with the flap 33 upon the pin 26 of the curler D, whence the said curler is fixed with the clamp by the pin 26 resting in the notch 25 and the prong 24 engageable selectively with the slot in the lug end 28 of said pin.

5 The insulator body 10, and also the protector C, avoids against scalp pulling and scalp burning in the use of the device.

10 The bars 13 and 14 have fixed thereto at their sides, adapted to confront the head of a user of the device, felt strips 34, being coextensive with 15 said bars and are cushioning elements for the clamp.

15 The protector C, when superimposed upon the clamp B, prevents the steam or heat from penetrating the scalp and its flap 33 absorbs, together with the pad 29, all steam and heat in the use of the device in a permanent waving machine, being 20 no liability of scalp pulling or scalp burning through such use.

25 What is claimed is:

25 1. A protector for a hair curling device having a clamp provided with a saddle head at one end and a prong at the other end and a curler for seating in the head and engageable with the prong comprising a flexible pad slotted intermediate and near opposite ends, the end slots accommodating the head and prong, and a flap on the pad following the intermediate slot and intercurled with strands of hair about the curler.

30 2. A protector for a hair curling device having a clamp provided with a saddle head at one end and a prong at the other end and a curler for seating in the head and engageable with the prong

comprising a flexible pad slotted intermediate and near opposite ends, the end slots accommodating the head and prong, a flap on the pad following the intermediate slot and intercurled with strands of hair about the curler, and a fibrous insulator body having an entrance slot for the strands of hair when engaged by the clamp and underlying the latter.

3. A protector for a hair curling device having a clamp provided with a saddle head at one end and a prong at the other end and a curler for seating in the head and engageable with the prong comprising a flexible pad slotted intermediate and near opposite ends, the end slots accommodating the head and prong, a flap on the pad following the intermediate slot and intercurled with strands of hair about the curler, and a fibrous insulator body having an entrance slot for the strands of hair when engaged by the clamp and underlying the latter, the said pad being superposed to the clamp.

4. A protector for a hair curling device having a clamp provided with a saddle head at one end and a prong at the other end and a curler for seating in the head and engageable with the prong comprising a flexible pad slotted intermediate and near opposite ends, the end slots accommodating the head and prong, a flap on the pad following the intermediate slot and intercurled with strands of hair about the curler, a fibrous insulator body having an entrance slot for the strands of hair when engaged by the clamp and underlying the latter, the said pad being superposed to the clamp, and cushions at the under side of the clamp and having contact with the said insulator body.

VICTORIA PARMENTEL.
